UNITED STATES PATENT OFFICE.

STANHOPE BOAL, OF PIQUA, OHIO.

DESIGN FOR A GAS-STOVE.

SPECIFICATION forming part of Design No. 26,851, dated March 30, 1897.

Application filed February 11, 1897. Serial No. 623,016. Term of patent 7 years.

To all whom it may concern:

Be it known that I, STANHOPE BOAL, residing at Piqua, in the county of Miami and State of Ohio, have invented a certain new and useful Design for a Gas Stove or Range, of which the following is a specification.

My invention relates to a design for gas stoves or ranges.

The leading feature of my design consists of a raised scrollwork of the style known as "rococo."

The features of my invention will be more fully set forth in the description of the accompanying drawing, making a part of this specification, in which the figure represents a perspective view of a gas-range with my design applied to the various parts.

A represents the base-frame and legs, the surfaces of which are curved and ornamented with raised scrollwork with pattern figures of the form shown in the drawing.

B represents the oven-door, which has the central portion ornamented with scroll figures raised, forming a border for the name-plate and terminating on the raised handle which forms a part of the scroll design. The edges of the door are also ornamented with border-like scrolls of the style above mentioned.

C represent the side frame-plates each side of the oven-door having network in one portion of the same, either open or closed, with peculiar scroll figures embodying the shell form of rococo design partially surrounding the network.

D represents the front of the stove above the oven-door and side plates. This is ornamented with the raised scrollwork of the design shown.

The central portion E represents the broiler-door, and it is ornamented with the raised scroll and net work of the same general design already described.

My design presents the general appearance of the raised scrollwork, network, and shell form of rococo design, forming a harmonious ornamentation over the entire front of the stove.

Having described my invention, I claim—

1. The design for a gas stove or range, substantially as herein shown and described.

2. In a gas stove or range the design for the base-frame and legs, substantially as herein shown.

3. In a gas stove or range the design for the oven-door, substantially as herein shown.

4. In a gas stove or range the design for the side plates, substantially as herein shown.

5. In a gas stove or range the design for the front plate above the oven-door and side plates, substantially as herein shown.

6. In a gas stove or range the design for the broiler-door, substantially as herein shown.

In testimony whereof I have hereunto set my hand.

STANHOPE BOAL.
